UNITED STATES PATENT OFFICE.

GEORGE H. HILL, OF DERBY, ASSIGNOR OF ONE-HALF TO WILLIAM J. WELSH, OF BIRMINGHAM, CONNECTICUT.

EXPANSIBLE BIT.

SPECIFICATION forming part of Letters Patent No. 313,735, dated March 10, 1885.

Application filed January 21, 1885. (No model.)

To all whom it may concern:

Be it known that I, GEORGE H. HILL, a citizen of the United States, residing at Derby, in the county of Fairfield and State of Connecticut, 5 cut, have invented certain new and useful Improvements in Expansible Bits; and I do hereby declare the following to be a full, clear, and exact description of the invention, such as will enable others skilled in the art to which it applies to make and use the same.

My invention relates to that class of bits which, in addition to the usual spur and cutter of regulation gage, is provided with a detachable and adjustable cutter and spur, so that the 15 ordinary gage of the bit may be doubled or trebled, or the adjustable cutter may be set at any intermediate gage.

Heretofore in this class of bits the adjustable cutter has been secured by means of one or 20 more set-screws. The object of my invention is to dispense with the use of set-screws and to produce a means of locking the adjustable cutter in any desired position which shall be economical in cost, easy and quick to adjust, and 25 not liable to get out of order or to wear out. With these ends in view I have devised the simple and novel means of adjusting and locking the cutter which I will now describe in connection with the accompanying drawings, 30 forming part of this specification, in which—

Figure 1 is a view of the device complete, the parts all being in operative position, and showing the adjustable cutter in side elevation. Fig. 2 is a similar view with the adjustable cutter in end elevation. Fig. 3 is a view with the adjustable cutter in side elevation, the cam-lever being turned so as to release the sliding block, and the screw which retains the sliding block being removed. Fig. 4 is a rear view of 35 the adjustable cutter detached, and Fig. 5 is a rear view of the cam-lever detached.

A represents the shank of the bit, B the cutter, C the spur, and D the gimlet, which are of ordinary construction, except that one side 45 of the shank is cut away, as at E, nearly down to the cutter. Just above the cutter is an undercut shoulder, E', the plane of which, besides inclining downward and backward from the front, lies at an angle which approximates a 50 right angle to the shank of the bit.

G is the adjustable cutter, which is provided

with a cutting-edge, G', and a spur, G². Upon the back of the adjustable cutter is an undercut shoulder, H, which corresponds exactly with shoulder F upon the bit. The upper edge, 55 I, of the adjustable cutter inclines outward, as shown in Fig. 2.

K is a sliding block, which is secured to the shank by a screw, K', which passes through slot L, thus leaving the block free to slide. The upper edge, M, of the sliding block is an inward curve, but is not a perfect arc, as will be more fully explained. The lower edge, N, is undercut and lies over the upper edge, I, of the adjustable cutter, the planes of the two edges 65 being beveled to correspond.

O is the securing-lever, which is pivoted to the shank by screw O', and is provided at its lower edge with a curved surface, P, which, however, is not an arc, and which acts as a cam 70 upon the curved upper edge, M, of the sliding block, to force the latter down upon the adjustable cutter, thus locking it in place. When it is desired to shift the adjustable cutter, the securing-lever is turned off, as in Fig. 3, which 75 leaves the sliding block loose, so that the adjustable cutter may be set at any desired adjustment.

I preferably make gage-marks, as at G³, upon the face of the adjustable cutter, so that it may 80 be instantly and accurately adjusted to bore any sized hole within its capacity.

The drawing shows a half-inch bit full size. If a half-inch hole is desired, the adjustable cutter is of course removed. If a larger hole 85 is required, the adjustable cutter is inserted and locked at the desired adjustment by the cam-lever. In practice a half-inch bit may be expanded to bore a one-and-one-half-inch hole, or a hole of any intermediate gage; or the adjustment may be changed from one gage to another without loss of time and without the use of other tools to lock and unlock the adjustable cutter.

In practice I preferably make the sliding 95 block slightly large, and leave it quite loose upon the surface of the shank, as indicated in Fig. 2. By this means I am enabled to take up the lost motion should the sliding block and the cam-lever become slightly worn after 100 long-continued use.

It will be observed that I have shown the

surface of the upper part of the cut-away portion of the shank as slightly rounded, as at E². This rounded portion engages the depression or hollow O² in the back of the cam-lever, thus 5 securing the lever in its locking position, there being sufficient spring in the lever to allow the edges of the depression to pass over the rounded portion E² of the shank.

It will of course be understood that I do not 10 desire to limit myself to the exact construction which I have shown, as it is evident that the details may be varied within reasonable limits without departing from the spirit of my invention.

15 I claim—

1. The combination, with the bit and an adjustable cutter, of a sliding block above the cutter and in contact therewith, and a cam adapted to engage the block, whereby the latter is caused to lock the adjustable cutter in 20 any desired position.

2. A bit of ordinary construction having its shank cut away upon one side, leaving an undercut shoulder, E', and an adjustable cutter 25 having a corresponding shoulder engaging therewith, and an outwardly-inclined upper edge, in combination with a sliding block which

engages the cutter, and a cam which acts upon the block to lock the cutter in any desired position.

3. A bit having one side of its shank cut away, substantially as shown, and an undercut shoulder, E', and an adjustable cutter having a shoulder corresponding therewith, and an inclined upper edge, in combination with 30 a sliding plate having a slot for a retaining-screw, an undercut lower edge and a curved upper edge, and a lever whose lower edge acts as a cam upon the sliding block, whereby the adjustable cutter is locked in place.

4. The bit having its shank cut away, as shown, and rounded, as at E², and an adjustable cutter, in combination with a sliding block, and a lever whose lower end acts as a cam upon the sliding block, and whose upper 40 end is provided with a hollow or recess, O², which engages the rounded portion E², to hold the lever in place.

In testimony whereof I affix my signature in presence of two witnesses.

GEORGE H. HILL.
